United States Patent Office

Des. 229,246

Patented Nov. 13, 1973

229,246

TIRE

Harold D. Fetty, Birmingham, Mich., and Arthur L. Finley, Akron, Ohio, assignors to The Goodyear Tire & Rubber Company, Akron, Ohio

Filed Feb. 24, 1972, Ser. No. 229,240

Term of patent 14 years

Int. Cl. D12—15

U.S. Cl. D90—20 R

The figure is a perspective view of a tire showing our new design, it being understood that the design is repeated throughout the circumference of the tire, the opposite side being substantially the same as that shown.

We claim:

The ornamental design for a tire, substantially as shown and described.
